UNITED STATES PATENT OFFICE.

HENRY L. SCHMIDT, OF WESTLEY, CALIFORNIA.

OPERATING-LEVER FOR GREASE-CUPS.

1,236,883.

Specification of Letters Patent. Patented Aug. 14, 1917.

Application filed March 2, 1917. Serial No. 151,877.

To all whom it may concern:

Be it known that I, HENRY L. SCHMIDT, a citizen of the United States, residing at Westley, in the county of Stanislaus, State 5 of California, have invented certain new and useful Improvements in Operating-Levers for Grease-Cups; and I do declare the following to be a full, clear, and exact description of the same, reference being had 10 to the accompanying drawings, and to the characters of reference marked thereon, which form a part of this application.

This invention relates to improvements in operating means for grease cups. The object of the invention being to produce a mechanism whereby leverage can be applied against the movable cap of the cup to force it to turn under all conditions. In cups now commonly used the movable caps have no 15 independent operating means and in order to force the grease out of the cup it is necessary to turn the cap by hand. When heavy grease is used or in cold weather when the grease hardens this sometimes becomes a 20 very difficult thing to do. Also some grease cups are positioned in such awkward and inaccessible places that it is almost impossible to grip the cap firmly enough to allow of it being easily turned. The aim of my invention is 25 to overcome these difficulties and provide an independent operating handle or lever for the cap whereby the same can be easily forced to move under any and all of the above conditions.

30 A further object of the invention is to produce a simple and inexpensive device and yet one which will be exceedingly effective for the purposes for which it is designed.

These objects I accomplish by means of 35 such structure and relative arrangement of parts as will fully appear by a perusal of the following specification and claims.

In the drawings similar characters of reference indicate corresponding parts in the 40 several views.

Figure 1 is a side elevation of a grease cup showing my improved operating lever thereon.

Fig. 2 is a top plan view of the same.

Fig. 3 is a vertical section through the 50 grease cup.

Referring now more particularly to the characters of reference on the drawings the numeral 1 designates the grease cup proper and 2 designates the movable cap thereon, 55 both of these members being of the usual type. In providing my improved invention I form around the upper edge of the cap 2 a plurality of notches or ratchets 3. A lever or handle 4 is pivotally mounted in any 60 desired manner to any desired part of the cap 2 but preferably to the center of the top thereof as at 5. This lever 4 is provided with a spring pressed dog 6 arranged to move freely over the ratchets 3 when the 65 lever 4 is moved contra-clockwise with respect to the cap 2. When moved in the opposite direction however, which is the direction in which the cap moves to force the 70 grease out of the cup, the said dog 6 engages one of the ratchets 3 and forces the cap 2 to turn with the movement of the 75 said lever 4.

The lever 4 can be made of such length as is necessary to provide a leverage to force 75 the grease through the cup under all ordinary conditions. The ratchets 3 can be spaced a distance apart as found desirable and by this means the cups can be positioned in awkward or inaccessible places and still 80 the lever 4 can be operated to turn the same even if only a slight space is allowed for the movement thereof.

From the foregoing description it will be readily seen that I have produced such a 85 device as substantially fulfills the object of the invention as set forth herein.

While this specification sets forth in detail the present and preferred construction of the device, still in practice such deviations 90 from such detail may be resorted to as do not form a departure from the spirit of the invention as defined by the appended claims.

Having thus described my invention what I claim as new and useful and desire to secure by Letters Patent is:

1. A grease cup having a cap turnable thereon adapted to force the grease through

the cup and a lever mounted on the cap and operable to turn the same.

2. A grease cup having a cap turnable thereon adapted to force the grease through the cup and a lever pivotally mounted on the cap and operable to turn the same.

3. A grease cup having a cap turnable

thereon adapted to force the grease through the cup and a lever pivotally mounted on the cap and provided with a spring pressed dog, 10 the cap being provided with ratchets engageable by the dog.

In testimony whereof I affix my signature.

HENRY L. SCHMIDT.
